UNITED STATES PATENT OFFICE.

HENRY F. ADAMS AND WILLIAM BERRY, OF SYRACUSE, NEW YORK.

IMPROVEMENT IN KEROSENE-LAMP BURNERS.

Specification forming part of Letters Patent No. 35,660, dated June 24, 1862.

To all whom it may concern:

Be it known that we, HENRY F. ADAMS and WILLIAM BERRY, of the city of Syracuse, county of Onondaga, and State of New York, have invented certain new and useful Improvements in Lamp-Heads; and we do hereby declare and ascertain the same, reference being had to the accompanying drawings, in which—

Figure 1 is an external view of our lamp-head attached to an ordinary lamp. Fig. 2 is a perspective view of the lamp-head and wick-fork with the cap C removed. Fig. 3 is a top view of the lamp-head with cap C removed. Fig. 4 is a bottom view of the lamp-head with the ordinary screw lamp-top, T, secured in its center by means of radial arms. This screw lamp-top and the cap C are of ordinary construction.

The object of our invention is to supply, in a peculiar manner, a sufficient quantity of air and draft, and in such peculiarly-arranged currents to the flame of ordinary kerosene and other carbonaceous oil lamps as to cause them to burn brightly and free from smoke, and with a wide and steady flame, without the necessity of using glass chimneys or tubes, which are very inconvenient and liable to be broken in use or cracked by the effect of the heat.

Our invention consists of a wick-tube (made somewhat larger than those heretofore used) which is surrounded by a conical-shaped air-chamber, A, made at its lower end considerably larger than the screw-top T, and secured to it by radial arms, so as to leave openings through which air can pass freely up the air-chamber through said openings. Around the bottom of this air-chamber we form a large concave flange, F, which serves to gather the air and concentrate it through the bottom openings into the air-chamber, which, growing smaller at the top, continues to increase the rapidity of the volume of ascending air

until arriving at the small concave flange R, having a small opening on each side next to the wick-tube and near its top. Through these openings a jet of air is forced up directly on the flame to support the flame against lateral currents of air, while the air which rises and is forced through the openings between the outer sides of the said small flange R and the inner sides of the cap C is divided into peculiarly-formed currents which tend to spread the flame, and the two sets of openings combined operate to support and spread the flame and supply it with abundance of air or oxygen to support perfect combustion and produce a steady, broad, and clear flame, and while it is thus rendered portable and convenient in every respect, it is also smoke-consuming and free from any offensive odor.

Any convenient device may be adopted for raising and lowering the wick, one very cheap form of which consists of a small fork, as sometimes used in camphene-lamps, or the ordinary ratchet wick-elevator in common use on kerosene-lamps may be used in our improved lamp-head for that purpose.

Having thus fully described our invention, what we claim as new, and desire to secure therein by Letters Patent, is—

The combination of the large concave flange F and conical air-chamber A, (having bottom openings, as described,) with the small concave flange R, (inclosed within the cap C,) and said flange R being constructed with peculiarly-formed center and outside openings, as specified, and the whole being combined and arranged specifically as described, and for the purposes set forth.

H. F. ADAMS.
WILLIAM BERRY.
